MACHINE FOR REPAIRING KNITTED FABRICS

Application filed April 23, 1929. Serial No. 357,425.

The invention relates to a machine for repairing knitted fabrics.

The object of the present invention is to provide for repairing knitted fabrics a simple, practical and efficient machine of strong, durable and comparatively inexpensive construction designed particularly for mending the ladder-like runs in silk stockings, and capable of enabling a silk stocking to be readily placed in proper position to be operated on by a single needle and of securely holding the same in such position during the repair operation and of simultaneously automatically advancing the needle along the run to be mended so that the needle will operate successively on the said ladder-like runs and repair the same in a manner similar to repairing such runs by hand.

A further object of the invention is to provide means for varying the feeding operation or movement of the needle longitudinally of a run to adapt the machine to the particular character of the stocking or other piece of knitted fabric to be repaired.

Another object of the invention is to provide means for enabling the needle and needle actuating mechanism to be disconnected from the feeding means to enable the needle to be manually adjusted and readily arranged in proper position for operating on a run and to be quickly returned automatically to its initial position after the operation of repairing a run has been completed.

With these and other objects in view, the invention consists in the construction and novel combination and arrangement of parts hereinafter described, illustrated in the accompanying drawings, and set forth in the claims hereto appended, it being understood that various changes in the form, proportion, and minor details of construction, within the scope of the claims, may be resorted to without departing from the spirit of the invention or sacrificing any of the advantages thereof.

In the drawings:

Figure 1 is a side elevation, partly in section, of a stocking mending machine constructed in accordance with this invention.

Fig. 2 is a longitudinal sectional view of the same.

Fig. 3 is an end elevation, partly in section, with parts removed to illustrate the construction for imparting a step by step movement to the spiral feed shaft. 55

Fig. 4 is a detailed sectional view illustrating the construction of the eccentric, the connecting bar, and the clutch for actuating the spiral feed shaft. 60

Fig. 12 is a detailed central longitudinal sectional view of the form or mandrel shown in Fig. 11.

Fig. 13 is an end view of the hollow slideable head. 80

Fig. 14 is a longitudinal sectional view of the hollow slideable head illustrating the cam actuated mechanism for moving the needle bar upwardly.

Fig. 15 is a detailed sectional view illustrating the construction of the movable member of the nut of the spiral feed screw and the means for releasing the latter. 85

Fig. 16 is a side elevation, partly in section, of the hollow slideable head. 90

Fig. 17 is a detailed horizontal sectional view of the same.

Fig. 18 is a fragmentary view of the machine illustrating the cam actuated mechanism for moving the needle bar upwardly and downwardly. 95

Fig. 19 is a horizontal sectional view through the cam actuating mechanism.

Fig. 20 is an enlarged detail fragmentary view illustrating the cam mechanism when 100

the cam is thrown to its downward position as distinguished from the upward position shown in Fig. 18.

Fig. 21 illustrates a rear elevation of the cam actuating mechanism.

In the accompanying drawings, in which is illustrated the preferred embodiment of the invention, the machine for repairing knitted fabrics comprises in its construction a vertically reciprocating needle bar 1 mounted in a hollow head 2 and guided in aligned vertical openings 3 and 4 in the top and bottom walls or portions of the hollow head, as clearly illustrated in Fig. 1 of the drawings. The hollow head, which is disposed transversely of the machine, is slidable longitudinally thereof to carry or feed the needle 5 of the needle bar along the run of the stocking to be repaired. The needle 5 is secured in a socket in the lower end of the needle bar 1 by means of a set screw 6 which clamps the needle to the needle bar. The hollow head is approximately L-shaped, as shown, and it is supported and guided in its sliding movement longitudinally of the machine by means of an upper rod 7, a central longitudinal shaft 8, and shafts 11 and 12 located at the bottom portion of the head. The said rod 7 and shafts extend longitudinally of the framework of the machine and connect end frames 13 and 14, which are mounted upon a suitable base or table 15. The base 15 and the end frames 13 and 14 constitute the framework of the machine. The connecting rod 7, which is located at the top of the framework of the machine, is secured in suitable openings of the end frames 13 and 14, by means of set screws 16. The horizontal rod 7 rigidly connects the upper portions of the end frames, which are rigidly secured at their lower portions to the table or base, whereby a rigid framework for the machine is provided. The shaft 8 is journaled in suitable bearings 17 and 18 of the end frames 13 and 14, the bearings 17 and 18 being preferably provided with bushings, as shown, and the said shaft 8 is provided with a longitudinal groove 19 in which slides a key 20 of a cam 21 carried by the slidable head and movable with the same for actuating the needle bar. The cam is provided with a cam groove 22 which operates a roller 23 of a lever 24 fulcrumed on a rod or pivot 25 carried on the slidable head. The lever 24 is approximately L-shaped and has a forwardly extending arm which is provided at its outer end with a recess 26 formed in the upper face of the arm of the lever and receiving a projecting pin 27 of the needle bar, whereby the lever 24 when actuated by the cam 21 will engage the pin 27 beneath the same and positively move the needle bar upwardly, as clearly illustrated in Fig. 14 of the drawings.

The needle bar is provided with a horizontally projecting arm 28 which is engaged by

a coiled spring 29 for yieldably moving the needle bar downwardly. The coiled spring is arranged on an adjusting screw 30 and is interposed between the horizontal arm 28 and the upper wall of the chamber of the hollow head, and the said screw 30, which is threaded into the top of the hollow head, is provided at its lower end with a suitable stop 31 preferably in the form of a head or collar for limiting the downward movement of the needle. The screw 30 is adjustable in the threaded opening in the top of the hollow head to arrange the needle bar stop 31 at the desired elevation. The collar or head 31 will limit the downward movement of the needle bar, and the coiled spring 29, which actuates the needle bar in such downward movement, will permit the needle bar to be limited in its downward movement. By this construction the reciprocation of the needle bar and the needle may be adjusted to suit the character of the stocking or other knitted fabric to be repaired. When the shaft 8 is rotated the cam 21, which is slidably interlocked with the groove 19 will also be rotated and will actuate the needle bar in the upward movement of its reciprocation, while the coiled spring 29 will actuate the needle bar and the needle in the downward movement of its reciprocation.

The shaft 8 is extended beyond the end frame 14 and has secured to it at this end of the machine a grooved pulley 32 which is connected by a suitable belt 33 with a pulley of an electric motor or other suitable source of power. The shaft 8 is provided at its other end with a combined hand wheel and fly wheel 34, by means of which the needle may be manually adjusted in applying the same to the stocking or other knitted fabric to be repaired.

The needle is provided at its lower end with a hook 35, and it has a swinging latch 36 pivoted at 37 above the hook. When the pivoted latch 36 is open it exposes the hook 35, and when the latch is closed it covers the throat or opening leading into the hook and forms an eye. The last perfect loop of the fabric is placed in the hook 35, and as the needle descends the loop slides upwardly on the shank of the needle, opening the latch and moving up on the needle until the latch 36 is released. The latch when released drops by gravity and falls over the next cross thread in the broken fabric. The loop remains on the shank of the needle and as the needle rises the hook 35 catches the thread and the latch closes over the hook, forming an eye and enclosing and confining the thread. The thread is then pulled through the loop, forming another loop, and this process is continued until all of the cross threads are looped through the fabric.

The slidable head and the needle are fed forward during the said operation of repair-

ing the run in the said fabric, by feeding mechanism comprising the shaft 11 located at the lower portion of the slidable head near the center of the same and provided with a spiral groove 41 which is engaged by a pivoted member 42 of a nut carried by the said lower portion of the slidable head. The nut is formed by a substantially semi-cylindrical recess 43 in the bottom of the slidable head, and the pivoted member 42, which is also provided with a substantially semi-cylindrical recess 44, has a flange 45 forming a partial thread and engaging in the spiral groove 41 at the bottom of the shaft 11, as clearly illustrated in Fig. 2 of the drawings. When the shaft 11 is intermittently rotated by the means hereinafter described, the slidable head will be moved forwardly with a step by step movement. The nut member, which extends across the bottom of the head from front to rear, is hinged at its front end to the bottom of the head by a suitable pintle 46, and its rear end is connected to the lower end of a coiled spring 47 secured at its upper end at 48 to the slidable head at the back thereof and adapted to yieldably maintain the hinged nut member 42 in its closed engaging position, as clearly illustrated in Figs. 12 and 13 of the drawings.

The hinged nut member is adapted to be swung downwardly out of engagement with the spirally grooved shaft 11 by means of an arm 49 carried by the slidable head and slidably interlocked by a key 50 with the shaft 12, which is provided with a longitudinal groove 51. The groove 51 of the shaft 12 receives the key 50 of the arm 49, which has a bifurcated outer portion 52. The bifurcated outer portion 52 straddles the coiled spring 47 and is provided with a lower cam face arranged to engage the hinged nut member 42 when the arm 49 is swung downwardly by the movement of the shaft 12. This will disengage the slidable head from the spirally grooved shaft 11 and permit the said head to slide freely along the shaft 11 and the rods 7 and 12 for enabling the slidable head and the needle to be manually adjusted to arrange the needle in proper position with relation to the run to be repaired, and also for the purpose of enabling the slidable head and the needle to be automatically returned to the initial position by a spring actuated reel 53 which is connected with the slidable head by a wire 54 or other suitable flexible connection. The reel 53 is mounted on a suitable pin or pivot 55 on the lower portion of the end frame 14, and the wire 54 extends upwardly from the reel to a guide wheel or pulley 56 mounted on the upper portion of the end frame 14. The wire 54 extends from the guide wheel 56 to the slidable head, and is secured to the same by means of an eye 57 or other suitable attaching means. The spring actuated reel may be of any desired construction, and the spring of the reel is under tension, and is designed to

be sufficiently strong to return the head to its initial position. The end frame 14 is equipped with a spring bumper 58 for relieving the machine of jar when the slideable head is automatically carried to its initial position by the spring actuated reel. The spring bumper 58 is shown as a horizontal disposed coiled spring mounted on the end frame 24, but any other suitable cushioning means may, of course, be employed for relieving the machine of jar and shock when the slideable head is automatically returned to its initial position. 70 75

The spirally grooved feeding shaft 11, is journalized in suitable bearings 59 and 60 of the end frames 13 and 14, and the said bearings are preferably provided with bushings, as shown, but any other suitable form of bearings may, of course, be provided for the said shafts of the machine. One end of the spirally grooved shaft 11 is extended beyond the framework of the machine and has a terminal bearing portion 61 which is mounted in a suitable bearing 62 of a casing 63 mounted upon the end frame 24 at the exterior thereof, as clearly illustrated in Fig. 2 of the drawings. The casing contains the mechanism for transmitting a step by step movement from the shaft 8 to the spirally grooved shaft 11. This mechanism comprises in its construction an eccentric 64 mounted on the shaft 8 and connected with and actuating one end of a reciprocating connecting bar 65 which extends downwardly to and is adjustably connected with an oscillatory clutch operating arm 66. The clutch operating arm 66, which extends upwardly from the shaft 11 at an inclination, is preferably tapered upwardly as shown, and is provided at its lower enlarged end 67 with an opening receiving a clutch collar 68 secured to the shaft 11 by a key 69, but any other suitable means may, of course, be employed for fixing the clutch collar 68 to the spirally grooved shaft 11. The enlarged end of the oscillatory clutch operating arm 66 is provided with an annular series of interior recesses 70 in which are mounted rollers 71 adapted to bind against the walls of the recesses 70 and the clutch collar 68 when the operating arm or lever 66 is moved downwardly by the eccentric bar 65. The downward movement of the clutch lever carries the rollers 71 toward the reduced ends of the recesses, and the walls of the said recesses, which are arranged at an angle to the periphery of the clutch collar, cause the rollers to be wedged between said walls and the clutch collar, whereby the lever 66 is clutched to the collar and the shaft, and is adapted to partially rotate the spirally grooved shaft 11 during each downward movement of the clutch lever 66. The rollers are released during the upward movement of the clutch member, and the spirally grooved

shaft remains stationary during such movement.

The amount of rotary movement of the spiral feed shaft, and the consequent feed of the slidable head, is controlled by an adjustable connection between the lower end of the connecting bar 65 and the operating arm 66. The lower end of the bar 65 is pivoted to the clutch operating lever by a suitable pin or pivot 72, which is mounted on and carried by a slide 73 guided in a slot or bifurcation 74 of the upper end of the clutch lever and actuated by an adjusting screw 74^a mounted in suitable bearings 75 of the clutch lever and extending through a threaded opening 76. The slide is moved longitudinally by the adjusting screw to limit the amount of movement imparted to the clutch by the action of the eccentric. The slide is suitably guided in the slot or bifurcation preferably by being arranged in overlapping relation with the same, and a suitable lock nut 77 is mounted on the adjusting screw for securing the slide in its adjustment. When the motor or other source of power is operated and the shaft 8 rotated, the needle bar will be reciprocated and the feeding mechanism will be simultaneously operated to move the slidable head along the run to be repaired with a step by step movement, which may be varied to suit the character of the fabric and the distance between the threads of the ladder-like run.

The stocking to be repaired is supported on a stationary form 78 consisting of a relatively long tapering arm preferably formed integral with a standard 79 suitably secured to the base or table 15 and rigidly holding the stocking receiving form in position beneath the outer portion of the slidable head which extends over the form and which is movable longitudinally thereof, as clearly shown in Fig. 1 of the drawings. The form, which may be constructed of wood or any other suitable material, is provided with a longitudinal recess 80 in which are mounted opposite rows of pivoted levers 81 having projecting upper terminals 82 yieldably maintained in contact with each other, as clearly illustrated in Fig. 9 of the drawings, by means of coiled springs 83. The levers 81, which are pivoted or fulcrumed intermediate of their ends at 84, have lower parallel vertical arms and upper inclined converging arms and their projecting terminals form a toothed gauge and are adapted to be introduced between the threads of a ladder-like run for maintaining the threads of the said ladder-like run in proper position to be operated on by the vertically reciprocating needle for repairing the run by looping the threads together, as heretofore explained. The levers 81 are arranged in pairs, the members of each pair being disposed opposite each other as shown, and in Fig. 9 of the drawings the form is equipped at the opposite walls of the

recess 80 with bearing plates 85 having bearings formed by longitudinal grooves and receiving segmental lugs 86. The segmental lugs fit in the bearing grooves, but they may be mounted on horizontal pintle rods 87, as illustrated in Fig. 11 of the drawings. The coiled spring 83 of each pair is disposed horizontally and extends across the space between the horizontal lower arms of the levers, seated in recesses 88 of the levers and suitably secured to the latter.

The springs 83, which yieldably maintain the projecting terminals 82 of the upper ends of the levers in contact with each other, are adapted to permit the needle to wedge itself between the upper arms of the levers and spread the same during the downward movement of the needle. The stocking receiving form 78 is preferably provided at the top with a metal face plate 89 which is provided with a central longitudinal slot 90 through which the upper terminals 82 of the levers project. Instead of employing springs for yieldably maintaining the upper ends of the levers 81 normally in contact with each other, a rubber 91 may be interposed between the lower arms of the lever, as illustrated in Fig. 11 of the drawings, but any other elastic or yieldable means for maintaining the upper ends of the levers normally in contact with each other and for permitting the upper ends of the levers to be separated by the needle in the downward movement thereof.

The needle bar is adapted to be raised to an elevated position and held elevated when desired by means of a cam lever 92 consisting of a cam head and an operating arm and pivoted to the needle bar at the upper portion thereof by a suitable pin or pivot 93. The cam lever is adapted to have its operating arm swung downwardly to the position illustrated in Fig. 3 of the drawings to elevate the needle bar and the needle, and the pressure upon the head of the cam lever will prevent the lever from accidentally moving from such position and enable the lever to hold the needle elevated. The cam lever is adapted to be swung upwardly out of engagement with the slidable head to a non-supporting position, and it is maintained in such non-supporting position by a suitable locking device, preferably consisting of a spring actuated ball 94 operating in a transverse socket or opening 95 in the needle bar, and yieldingly pressed outwardly by a coiled spring 96, and adapted to automatically engage a recess or concavity 97 formed in the inner face of the head of the cam lever. The recess 97 is brought into register with the transverse opening 95 of the needle bar when the cam lever is swung to its non-supporting position, and the engagement of the spring actuated ball with the cam lever is sufficient to prevent accidental movement of the latter and at the same time the spring actuated ball will permit the cam lever

to be readily swung out of engagement with it when it is desired to move the cam lever to its supporting position. If desired, a depression may also be provided for engagement with the spring actuated ball when the cam lever is in its supporting position, and any other suitable locking device may, of course, be employed for holding the cam lever against accidental movement when in its supporting or non-supporting position.

The stocking to be repaired is held on the form in proper position with relation to the reciprocating needle by means of a foot 98 consisting of a plate extending horizontally from a stem 99 and having an upwardly curved terminal portion 100 extending in the direction of the movement of the slideable head in the feeding operation thereof, and adapted to pass over the stocking at opposite sides of the portion to be repaired and provided with an opening 101 for the passage of the needle and for exposing the threads of the ladder-like run to the operation of the needle. The stem 99 of the foot passes through a vertical opening 102 of the slideable head and at its lower portion below the head is curved at 103, the curved portion extending downwardly and forwardly in the direction of the needle, as clearly illustrated in Fig. 1 of the drawings.

The foot is adapted to be lifted out of the way to permit a stocking to be placed on and removed from the form and it is provided intermediate of the ends of its stem with a projection 104 consisting of a pin or stud and extending into a slot 105 of an arm 106 of an angle operating lever 107. The angle operating lever 107 is pivoted at its angle to the exterior of the slideable head by means of a suitable pin or pivot 108, and it is provided with a suitable operating handle 109 adapted to be readily grasped by the operator for swinging the angle lever and elevating the foot. The weight of the operating arm of the lever is sufficient to maintain the foot in an elevated position, and when the operating arm of the angle lever is swung upwardly to lower the foot into operative guiding position, the said operating arm is arranged substantially in a perpendicular position so that the weight of the foot and its stem will prevent any accidental movement of the operating lever of the foot. The foot is also provided in its lower face with a groove 110 to enable it to straddle the toothed gauge formed by the projecting terminals of the levers 81. The groove or channel in the lower face of the foot intersects the slot or opening 101 for the passage of the needle, and in practice the slot or opening of the foot may extend from the curved end to the stem, forming a foot of two side portions connected at their rear ends by the stem which is grooved or slotted to provide the necessary clearance for the projecting terminals of the

levers 81. The machine is also provided at one end with an operating lever 111 consisting of an arm secured to one end of the shaft 12 and adapted to be operated for partially rotating the shaft 12 to swing the arm 49 downwardly for opening the nut member 42 and disengaging the nut from the spirally grooved shaft 11. When the operating arm or lever 111 is swung in the opposite direction to raise the arm 49, the nut will be automatically closed by the spring 47.

What I claim is:

1. A machine for mending runs in fabrics including a vertically reciprocating needle, means for operating the needle to manipulate the threads of a run in the fabric to close the run, and means for carrying the needle along the run for successive operation on the threads thereof.

2. A machine for mending runs in fabrics including a vertically reciprocating needle, means for operating the needle to manipulate the threads of a run in the fabric to close the run, and means for carrying the needle along the run by a step by step movement for enabling the needle to operate on the threads of the run.

3. A machine for mending runs in fabrics including a single operating needle mounted for vertical reciprocation and provided with means for manipulating the threads of a run to close the latter, means for supporting the fabric in position to be operated on by the needle, and means for carrying the needle over the fabric for operating on the threads of a run.

4. A machine for mending runs in fabrics including a form provided with means for supporting a fabric in a relatively stationary position, a vertically reciprocating needle provided with means for manipulating the threads of a run for closing the same, and means for carrying the needle horizontally along the form with an intermittent feeding movement to enable the needle to operate on the successive threads of a run.

5. A machine for mending runs in fabrics including a form adapted to receive and support the fabric and provided with projecting means arranged to hold the threads of the fabric in position for repairing a run, a needle reciprocating vertically above the form and provided with means for manipulating the threads of the fabric for closing a run, and means for carrying the needle to different positions over the form for operating on the successive threads of a run.

6. A machine for mending runs in fabrics, including an operating needle, and means cooperating with the needle to manipulate the threads of a run in the fabric to close the run, said means comprising projections arranged in pairs and yieldably maintained in normal position and adapted to be separated by the needle to afford a passage for the same.

7. A machine for mending runs in fabrics, including an operating needle, and means cooperating with the needle to manipulate the threads of a run in the fabric to close the run, said means comprising a toothed gauge adapted to receive the ladder-like threads of a run and composed of yieldably mounted elements arranged in pairs and adapted to be separated by the needle to afford a passage for the same.

8. A machine for mending runs in fabrics, including an operating needle, and means cooperating with the needle to manipulate the threads of a run in the fabric to close the run, said means comprising a toothed gauge composed of levers arranged in pairs and yieldably mounted, said levers being provided with projecting portions adapted to receive the ladder-like threads of a run and capable of being separated by the needle to permit the passage of the same between the levers.

9. A machine for mending runs in fabrics, including an operating needle, and means cooperating with the needle to manipulate the threads of a run in the fabric to close the run, said means comprising a toothed gauge composed of levers arranged in pairs and fulcrumed intermediate of their ends and having projecting outer portions adapted to extend between the threads of a run, and yieldable means operating on the inner portions of the lever and adapted to permit the outer portions to be separated by the needle.

10. A machine for mending runs in fabrics, including an operating needle, and means cooperating with the needle to manipulate the threads of a run in the fabric to close the run, said means comprising a toothed gauge having levers arranged in pairs and fulcrumed intermediate of their ends and provided with spaced inner portions and contacting outer portions, and yieldable means interposed between the inner portions of the lever and adapted to permit the outer portions to be separated by the needle.

11. A machine for mending runs in fabrics including an operating needle, and means cooperating with the needle to manipulate the threads of a run in the fabric to close the same, said means comprising a form adapted to receive the fabric and a toothed gauge carried by the form and composed of levers arranged in pairs and yieldably mounted within the form and having projecting outer portions arranged to extend between the threads of the run and adapted to be separated by the needle.

12. A machine for mending runs in fabrics including an operating needle, and means cooperating with the needle to manipulate the threads of a run in the fabric to close the same, said means comprising a stationary form adapted to receive a stocking and provided with a toothed gauge extending longitudinally of the form and composed of levers yieldably mounted within the form and having projecting outer portions extending between the threads of the run and adapted to be separated by the needle, and means for carrying the needle along the gauge for operating on the successive threads of the run.

13. A machine for mending runs in fabrics including a stationary form consisting of a projecting arm and a supporting portion arranged at one end of the arm, said arm being adapted to receive a stocking to be repaired, means carried by the arm for holding the threads in position, a vertically reciprocating needle provided with means for manipulating the threads of a run to close the same, and means for carrying the needle along the form for enabling the needle to operate on the successive threads of the run.

14. A machine for mending fabrics including a stationary form adapted to receive the fabric to be repaired, a head slidably mounted to move to different positions over the form, a needle carried by the head for vertical reciprocation therein and provided with means for manipulating the threads of the fabric to close a run in the same, mechanism for vertically actuating the needle carried by the said head, and means for operating the said mechanism.

15. A machine for mending runs in fabrics including a stationary form adapted to support the fabric to be repaired, a supporting frame, a head slidably mounted on the frame and movable over the form, a needle carried by the head for vertical reciprocation therein and provided with means for manipulating the threads of a run for closing the latter, a rotating shaft mounted on the frame, and mechanism mounted on the slideable head for operating the needle, said mechanism comprising a cam slidably interlocked with the shaft and actuated by the same.

16. A machine for mending runs in fabrics including a stationary form adapted to support the fabric to be repaired, a supporting frame, a head slidably mounted on the frame and movable over the form, a needle carried by the head for vertical reciprocation therein and provided with means for manipulating the threads of a run for closing the latter, a rotating shaft mounted on the frame, a lever fulcrumed on the head for actuating the needle, and a cam slidably interlocked with the shaft and cooperating with the lever for operating the same.

17. A machine for mending runs in fabrics including a frame, a head slidably mounted on the frame, a needle carried by the head for vertical reciprocation therein and provided with means for manipulating the threads of a run to close the latter, a rotating shaft journaled on the frame, and mechanism carried by the slideable head for

actuating the needle, comprising a cam slidably interlocked with the said shaft and movable along and rotated by the same, and a needle-actuating lever operated by the said cam.

18. A machine for mending runs in fabrics including a frame, a head slidably mounted on the frame, a reciprocating needle bar carried by the head, a rotating shaft

10 journaled on the frame, and mechanism for reciprocating the needle bar carried by the head and comprising a lever arranged to engage the needle bar and move the same in one direction, yieldable means for moving 15 the needle in the opposite direction, and a cam slidably interlocked with the shaft and connected with and operating the lever.

19. A machine for mending runs in fabrics including a frame, a head slidably mounted on the frame, a reciprocating needle bar carried by the head, a rotating shaft journaled on the frame, and mechanism carried by the slidably head for reciprocating the needle bar and comprising a cam slidably 25 interlocked with the shaft and rotating the same and provided with a cam groove, a lever fulcrumed at an intermediate point and provided at one end with means operating in the groove of the cam, the other end of the 30 lever being arranged to move the needle bar in one direction, and yieldable means for moving the needle bar in the opposite direction.

20. A machine for mending runs in fabrics 35 including a frame, a stationary form adapted to support the fabric to be repaired, a head slidably mounted on the frame, a vertically reciprocating needle carried by the head and provided with means for manipulating the threads of a run for closing the latter, mechanism for operating the needle also carried by the head, and a foot mounted on the head and movable with the same over the said form for retaining the fabric in position to be operated upon by the needle.

21. A machine for mending runs in fabrics including a frame, a stationary form adapted to support the fabric to be repaired, a head slidably mounted on the frame, a vertically reciprocating needle carried by the head and provided with means for manipulating the threads of a run for closing the latter, mechanism for operating the needle also carried by the head, a foot mounted on the head and movable with the same over the said form for retaining the fabric in position to be operated upon by the needle, and manually operable means mounted on the head for raising and lowering the foot.

22. A machine for mending runs in fabrics including a frame, a stationary form adapted to support the fabric to be repaired, a head slidably mounted on the frame, a vertically reciprocating needle carried by the head and provided with means for manipulating the

threads of a run for closing the latter, mechanism for operating the needle also carried by the head, a foot cooperating with the needle and provided with a stem mounted for vertical movement on the head for lowering the 70 foot to the form and raising it therefrom, and a manually operable lever carried by the head and connected with the stem of the foot for raising and lowering the latter.

23. A machine for mending runs in fabrics 75 including a frame, a head slidably mounted on the frame, a vertically reciprocating needle carried by the head and provided with means for manipulating the threads of a run to close the same, a shaft mounted on the 80 frame and having spiral feeding means carried with the head for moving the same along the frame, and means for intermittently imparting a partial rotation to the said shaft.

24. A machine for mending runs in fabrics 85 including a frame, a head slidably mounted on the frame, a vertically reciprocating needle carried by the head and provided with means for manipulating the threads of a run to close the same, a shaft mounted on the 90 frame and having spiral feeding means carried with the head for moving the same along the frame, and means for intermittently imparting a partial rotation to the said shaft, said means comprising an oscillating clutch 95 lever, a clutch connecting the lever with the said shaft and adapted to actuate the shaft when the lever is moved in one direction, and means for oscillating the said lever.

25. A machine for mending runs in fabrics 100 including a frame, a head slidably mounted on the frame, a vertically reciprocating needle carried by the head and provided with means for manipulating the threads of a run to close the same, a shaft mounted on the 105 frame and having spiral feeding means carried with the head for moving the same along the frame, and means for intermittently imparting a partial rotation to the said shaft, said means comprising an oscillating clutch 110 lever, a clutch connecting the lever with the said shaft and adapted to actuate the shaft when the lever is moved in one direction, and an eccentric having an eccentric rod connected with the clutch lever for oscillating the latter.

26. A machine for mending runs in fabrics including a frame, a head slidably mounted on the frame, a needle carried by the head and provided with means for manipulating the threads of a run to close the same, a shaft mounted on the frame and having spiral feeding means carried with the head for moving the same along the frame, and means for intermittently imparting a partial rotation to the said shaft, said means comprising an oscillating clutch lever, a clutch connecting the lever with the said shaft and adapted to actuate the shaft when the lever is moved in one direction, an eccentric having an ec- 115 120 125 130 135 140 145

centric rod pivotally connected with the clutch lever for actuating the latter, and means for moving the pivot of the connecting rod longitudinally of the lever to vary the amount of rotary movement imparted to the said shaft by each operation of the clutch lever.

27. A machine for mending runs in fabrics including a frame, a head slidably mounted on the frame, a vertically reciprocating needle carried by the head and provided with means for manipulating the threads of a run to close the same, a shaft mounted on the frame and having a spiral feeding portion, a nut for connecting the slidable head with the said shaft for moving the head along the shaft, and manually operable means for disengaging the nut from the shaft to permit free movement of the head.

28. A machine for mending runs in fabrics including a frame, a head slidably mounted on the frame, a vertically reciprocating needle carried by the head and provided with means for manipulating the threads of a run to close the same, a shaft mounted on the frame and having a spiral feeding portion, a nut for connecting the slidable head with the said shaft for moving the head along the shaft, means for disconnecting the head from the shaft, and means for automatically moving the head along the shaft to return the head to its initial position.

29. A machine for mending runs in fabrics including a frame, a head slidably mounted on the frame, a needle carried by the head and provided with means for manipulating the threads of a run to close the same, a shaft mounted on the frame and having a spiral feeding portion, a nut for connecting the slidable head with the said shaft for moving the head along the shaft, means for disconnecting the head from the shaft, and means for automatically moving the head along the shaft to return the head to its initial position, the last named means comprising a flexible connection attached to the head and guided on the frame, and yieldable means connected with the flexible connection for actuating the head.

30. A machine for mending runs in fabrics including a frame, a head slidably mounted on the frame, a needle carried by the head and provided with means for manipulating the threads of a run to close the same, a shaft mounted on the frame and having a spiral feeding portion, a nut for connecting the slidable head with the said shaft for moving the head along the shaft, means for disconnecting the head from the shaft, and means for automatically moving the head along the shaft to return the head to its initial position, said means including a flexible connection attached to the head and guided on the

frame and a spring actuated reel connected with the flexible connection.

31. A machine for mending runs in fabrics including a frame, a head slidably mounted on the frame, a vertically reciprocating needle carried by the head and provided with means for manipulating the threads of a run to close the same, a shaft mounted on the frame and having a spiral feeding portion, a nut for connecting the slidable head with the said shaft for moving the head along the shaft, an operating shaft having a manually operable device, and an arm carried by the head and slidably connected with the operating shaft and arranged to disengage the nut from the said spiral feeding portion.

32. A machine for mending runs in fabrics including a frame, a head slidably mounted on the frame, a vertically reciprocating needle carried by the head and provided with means for manipulating the threads of a run to close the same, a feeding shaft having a spiral feeding portion, a nut carried by the head and having a hinged member engaging the spiral portion of the feeding shaft, and yieldable means for holding the hinged nut member in engagement with the said shaft.

33. A machine for mending runs in fabrics including a frame, a head slidably mounted on the frame, a vertically reciprocating needle carried by the head and provided with means for manipulating the threads of a run to close the same, a feeding shaft having a spiral feeding portion, a nut carried by the head and having a hinged member engaging the spiral portion of the feeding shaft, yieldable means for holding the hinged nut member in engagement with the said shaft, an operating shaft mounted on the frame and provided with an operating device, and an arm slidably interlocked with the operating shaft and arranged to engage the hinged nut member for disconnecting the head from the feeding shaft.

34. A machine for mending runs in fabrics including a frame, a head slidably mounted on the frame, a vertically reciprocating needle carried by the head and provided with means for manipulating the threads of a run to close the same, mechanism also carried by the head for operating the needle, a continuously rotated power shaft journaled on the frame and connected with and actuating the needle operating mechanism, an intermittently rotated feeding shaft connected with the head for sliding the same along the frame, and mechanism for transmitting motion from the continuously rotating power shaft to the intermittently rotated feed shaft.

35. A machine for mending runs in fabrics including a frame, a head slidably mounted on the frame, a vertically reciprocating needle carried by the head and provided with means for manipulating the threads of a run to close the same, mechanism also carried by the

head for operating the needle, a continuously rotated power shaft journaled on the frame and connected with and actuating the needle operating mechanism, an intermittently rotated feeding shaft connected with the head for sliding the same along the frame, and mechanism for transmitting motion from the continuously rotating power shaft to the intermittently rotated feed shaft, the latter mechanism including an eccentric mounted on the power shaft, an oscillating lever actuated by the eccentric, and means for transmitting motion from the lever to the intermittently rotated shaft during the movement of the lever in one direction only.

36. A machine for mending runs in fabrics including a frame, a head slideable on the frame, a vertically reciprocating needle carried by the head and provided with means for manipulating the threads of a run to close the same, mechanism also carried by the head for operating the needle, a continuously rotated power shaft journaled on the frame and connected with and actuating the needle operating mechanism, an intermittently rotated feeding shaft connected with the head for sliding the same along the frame, and mechanism for transmitting motion from the continuously rotating power shaft to the intermittently rotated feed shaft, the latter mechanism including an eccentric mounted on the power shaft, a lever fulcrumed on the intermittently rotated shaft and connected with and oscillated by the eccentric, and means for transmitting motion from the lever to the intermittently rotated shaft during the movement of the lever in one direction only.

37. A machine for mending runs in fabrics including a frame, a head slideable along the frame, a vertically reciprocating needle carried by the head and provided with means for manipulating the threads of a run and closing the latter, a continuously rotating power shaft, mechanism carried by the head and slidably interlocked with the power shaft for operating the needle, a feed shaft journaled on the frame and having a spiral feeding portion, a nut carried by the head and engaging the spiral feeding portion of the shaft, and means for transmitting an intermittent rotary movement from the power shaft to the feeding shaft, comprising an eccentric element mounted on the power shaft, an oscillating lever actuated by the eccentric, and means actuated by the lever for rotating the feed shaft during the movement of the lever in one direction only.

38. In a machine for mending runs in fabrics, including an operating needle, and means cooperating with the needle to manipulate the threads of a run in the fabric to close the run, said means comprising projections arranged in pairs, and means for maintaining said projections in normal position and

yet permit separation of the same by the needle to afford a passage for the needle.

39. A machine for mending runs in fabrics including a frame, a head slidably mounted on the frame, a vertically reciprocating needle carried by the head and provided with means for manipulating the threads of a run to close the same, positive means for sliding the head on the frame, means for automatically moving the head along the shaft to return the head to its initial position, means for actuating the last named means, and cushioning means for engagement by the head for relieving the machine of shock when the head is automatically returned to its initial

position.

40. A device of the class described comprising a relatively long hollow form for the support of a relatively long stretch of the stocking to be mended and provided with a relatively long narrow longitudinally disposed slot for the passage of a needle operable through the fabric of the stocking and projecting into said slot, whereby to operate upon a long run in the stocking without shifting the stocking on the form, and pivotal members arranged in pairs within the hollow form and projecting outwardly through said slot and yieldably maintained in normal position and adapted to be separated by the needle to afford a passage for the needle.

41. A machine for mending runs in fabrics including a frame, a head slidably movable on the frame, a vertically reciprocating needle carried by the head and provided with means for manipulating the threads of a run to close the same, the head being slideable along the run in a definite path thereover to present the needle to the run to successively operate on the threads thereof.

42. A machine for mending runs in fabrics including a frame, a head slidably movable on the frame, a vertically reciprocating needle carried by the head and provided with means for manipulating the threads of a run to close the same, the head being slideable along the run in a definite path thereover to present the needle to the run to successively operate on the threads thereof, and means for automatically returning the head to its initial position.

43. In an apparatus of the type described, the combination comprising a fixed spacer bar having teeth thereon for supporting the transverse threads of a run in knitted or similar fabrics, a vertically reciprocable needle supported over the spacer bar and means for moving the needle bar along the spacer bar and for vertically oscillating the needle bar.

44. In an apparatus of the type described, the combination comprising a support, a rotatable shaft in said support, a threaded rotatable shaft in said support, a head slidably mounted on said first shaft and engaging

said threaded shaft, a vertically movable needle bar in said head, means for rotating said threaded shaft from said first shaft, fixed spacer bars attached to said support having teeth on their upper edges and means actuated by said rotatable shaft and connected to said needle bar for oscillating it.

In testimony whereof I have hereunto set my hand, this 15th day of April, 1929.

JOSEPH S. PECKER.
